Primary Examiner — Marissa J Cash(74) *Attorney, Agent, or Firm* — Millman IP Inc.(57) **CLAIM**

The ornamental design for a flying device, as shown and described.

DESCRIPTION

FIG. 1 is a perspective view from above, to the front and to one side of the new design for a flying device;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the evenly spaced broken lines depict portions of the flying device that form no part of the claimed design, and the dash-dot lines represent boundaries that form no part thereof.

1 Claim, 7 Drawing Sheets(56)
